UNITED STATES PATENT OFFICE.

ELIAS VICTOR SEIXAS, OF PHILADELPHIA, PENNSYLVANIA.

UNIVERSAL GAS-WATER-HEATER CONTROL.

Application filed August 15, 1924. Serial No. 732,330.

To all whom it may concern:

Be it known that I, ELIAS VICTOR SEIXAS, a citizen of the United States, residing at Philadelphia, in the county of Philadelphia and State of Pennsylvania, have invented new and useful Improvements in Universal Gas-Water-Heater Controls, of which the following is a specification.

This invention relates to a control for gas water heaters of approved types, and an object of the invention is to provide means whereby the controlling of the ignition of the burner in the gas operated water heater may be controlled from points remote from the burner itself.

Another object of the invention is to provide a control means by means of which the burner valve may be opened from any desired position within the building without requiring the operator's going up and down the stairs to the heater which is usually positioned within the basement of the house, and also to provide control means constructed so that by a slight upward pressure at any point on the control means, it may be released to permit the closing of the valve and the cutting off of the supply of fuel to the burner.

Other objects of the invention will appear in the following detail description, and in the accompanying drawings which shows a diagrammatic view of a building illustrating the improved control positioned therein.

Referring more particularly to the drawings, the improved control is associated with a water heater 1 of any approved construction which includes the usual approved type of pilot light and burner (not shown) together with the valve structure 2 for controlling the supply of gas to the heater 1. The valve structure 2 has a control lever 3 connected thereto and extending transversely therefrom which control lever is in turn connected to a chain 4. The chain 4 passes upwardly from the heater and over a suitable guide pulley 5 then it passes from the guide pulley 5 to a second guide pulley 6 which may be positioned at any convenient location within the building. The chain 4 is then extended through the first floor 7 of the building and is connected to a rod 8. The rod 8 may extend through the succeeding upper floors indicated at 9 of the build-

ing to the uppermost floor or to the uppermost desired point in the building, depending upon the limits from which it is desired to control the heater. The rod 8 has eyelets 10 thereon at spaced points, one in each of the respective rooms through which it extends and it has a final eyelet 11 on its uppermost end. Hooks 12 are swingably supported from any suitable support within the building and when the rod 8 is moved upwardly one of the hooks close to which the operator is standing is slipped through one of the eyelets 10 for holding the rod and the chain 4 upwardly. The upward movement of the rod will rock the lever 3 and open the valve permitting the fuel passing to the burner to be ignited from the pilot light. When the water has been heated sufficiently, the operator gives a slight upward pressure on the rod 8 which will cause a releasing action of the hook 12, permitting the hook to fall by its own weight out of the eyelet of which it has been engaged, and allowing the rod 8 to fall downwardly into its normal position under its own weight, while the chain 4 and lever 3 will be moved downwardly into valve closing position by means of the weight 14 on the lower end of the chain. If it is so desired, an eyelet 15 may be carried by the chain 4 in close proximity to the burner 1 for co-operation with a hook 16 which may be suspended or supported in any suitable manner, such as by the flexible support 17, thereby permitting the control to be operated from a point in close proximity to the heater 1.

It is, of course, to be understood, that the invention may be constructed in various other manners and the parts associated in different relations, and therefore, I do not desire to be limited in any manner, except as set forth in the claims hereunto appended.

What I claim is:

1. The combination with the control valve of the burner of a gas water heater, of a control rod, flexible means connecting said control rod to said valve, eyelets on said rod and swingably supported hooks for engagement in said eyelets.
2. The combination with the fuel control valve, of a gas water heater, of a lever connected to the valve, a control rod, flexible means connecting the control rod to the

lever, eyelets on the rod at spaced points, and swingably supported hooks for engagement with said eyelets.

3. The combination with the fuel control valve, of a gas water heater, of a lever connected to the valve, a control rod, flexible means connecting the control rod to the lever, eyelets on the rod at spaced points,

swingably supported hooks for engagement with said eyelets, and a weight on said flexible means for operating said lever and valve upon releasing engagement between any of said hooks and eyes.

In testimony whereof I affix my signature.

E. VICTOR SEIXAS.
